RADIO RECEIVING AND AMPLIFYING SYSTEM

Application filed July 18, 1928. Serial No. 293,671.

Our invention relates to electromagnetic wave receiving systems and more particularly to a means of securing amplification of such waves by means of such receiving system. It relates also to radio receiving systems and to methods of amplifying radio signals.

One of the primary objects of our invention and discovery is to provide means for combining similar radio impulses in such a manner as to secure sufficient power to operate loud speakers and the like without resorting to thermionic tubes or similar devices and, of course, artificially adapted power. A further object is to eliminate the necessity of either tubes or supplemental power and thereby to secure for radio waves a perfect method of amplification. One of the additional objects of our invention and discovery is to provide a means of amplifying the effects of relatively high-frequency waves at a distant point and to form a receiving circuit for power transmitted without wires which will have substantially perfect efficiency. This has hitherto, to our knowledge, never been attained.

The method employed to achieve this result lies in joining separate open receiving circuits and by means of induction transferring the power to a secondary circuit. The secondaries of each must be so combined that the increased current can in no way alter the magnetic field of each primary. By joining the secondaries in parallel with a variable condenser the operation of each primary circuit is left undisturbed when the secondary circuit is completed. Unless this is accomplished, the accumulation of power generated by the satisfaction of an inductive stress we have discovered to be impossible.

The annexed drawings and following description show in detail certain means of embodying a preferred form of our invention, said means illustrating, however, only a few of the ways in which our invention and discovery may be used together with the best modes in which we have contemplated applying the principle in such a manner as to distinguish it from other inventions.

In said annexed drawings:

Figure 1 is a diagrammatic view of the preferred form of our invention showing the wiring and the means used indicated by their symbolic designations;

Figure 2 shows a fragmentary diagrammatic view of the wiring of an optional use of a portion of the apparatus shown in Figure 1;

Figure 3 illustrates in detail a preferred form of power gathering means for use with the circuit of Figure 1 shown fragmentarily; and

Figure 4 shows a convenient means of controlling the apparatus shown in Figure 1, the capacity units being shown in detail and the balance of the circuit shown fragmentarily.

Referring to the same or similar elements by the same letters and numerals throughout the several views we designate by the letters A¹, A², A³, A⁴, and Aⁿ electrically separated antennæ spaced by the insulators I, and an end of each antenna being connected with a suitable lightning arrester and with one set of plates of the variable condensers C¹, C², C³, C⁴, and Cⁿ. The other connections of the lightning arresters L¹, L², L³, L⁴, and Lⁿ are shown in Figure 3 connected with the common ground G. Thus the antenna A¹ is joined with the condenser C¹, A² with C², A³ with C³, A⁴ with C⁴, and Aⁿ with Cⁿ.

The opposing plates of the condensers C¹, C², C³, C⁴, and Cⁿ, are severally joined in series with the primary induction coils P¹, P², P³, P⁴, and Pⁿ, the non-inductive variable resistance coils N¹, N², N³, N⁴ and Nⁿ and the ground G¹, G², G³, G⁴ and Gⁿ. It will be noted that the circuits A¹, C¹, P¹, N¹, G¹, A², C², P², N², G², A³, C³, P³, N³, G³, A⁴, C⁴, P⁴, N⁴, G⁴, and Aⁿ, Cⁿ, Pⁿ, Nⁿ, Gⁿ are electrically insulated from each other.

The secondary coils S¹, S², S³, S⁴ and Sⁿ are preferably closely coupled with the primary coils P¹, P², P³, P⁴ and Pⁿ respectively and are joined in parallel by the conductors 1 and 2 as shown in Figure 1. At the points 5 and 6 conductors 1 and 2 are joined by the conductors 3 and 4 which in turn are connected in series with a detector D and loud

speaker or other receiver R. In Figure 2 the conductors 3 and 4 are shown connected to the primary P of the step up transformer whose secondary S is in turn connected in series with the detector D and receiver R.

5 The variable condenser C is shown shunted between the conductors 3 and 4 and its operation and function will be hereinafter more fully described.

10 In Figure 4 the condenser units are shown in detail with insulating sprockets 7 adjustably fastened to the shafts of the condensers set in motion by the chain 8 when the dial 9 is turned.

15 The operation of the amplifying system is as follows:—

When the circuit is installed it is tested to determine the amount of power which flows in each primary circuit when a given wave length is received. The position of the condenser and the amount of current flowing in the microammeter or milliammeter M is noted. To make this test all of the secondaries are disconnected except the one whose primary circuit is being tested. When this test is being made the non-inductive resistances are made zero. After all the circuits have been tested and the one whose value is lowest is noted, the remaining circuits may be preferably reduced to the same value by means 20 of the resistances N¹, N², etc. With the condensers in their respective positions the chain 8 is placed in engagement with the sprockets, the sprockets being rotatably adjusted, if necessary, to properly register with the chain. 25

30 The secondary coils are then fastened to the conductors 1 and 2, and the circuit is ready for operation.

35 Of course, it will be readily apparent that the resistances N¹, N², etc., may be entirely omitted since without them the circuit is self-adjusting because of the fundamental law hereinbefore referred to which requires that any increase in the secondary circuit beyond that which the primary is capable 40 of inducing will operate to reduce the primary current to that fixed amount.

45 At this point the operation of the condenser C becomes important because, when the capacity C is reduced to zero, the value of the current produced by all of the circuits for a given wave will not exceed that produced by one. Therefore the capacity of the condenser C is adjusted until maximum current strength is recorded by the 50 meter M. The greater the amount of amplification of any wave, the greater the value of the capacity of C becomes in order to properly store the accumulated power.

55 60 It is within the contemplation of our invention to insulate severally and cable the antennæ. In that case loss due to radiation resistance will be high, but the use of induction screens between circuits is likewise 65 within the contemplation of our invention.

The closer the primary circuits are together the greater the mutual induction becomes and the lower the average efficiency of each circuit, but efficiencies as high as 80% of the theoretical efficiency of amplification or n^{70} times the value of current of one circuit where n represents the number of circuits with all the others disconnected can be easily attained. The transformer coils P¹ S¹, P² S², P³ S³, P⁴ S⁴, Pⁿ Sⁿ, may be either variable 75 or fixed and may have adjustable or fixed coupling. In the case of adjustable coupling they may be controlled by insulating sprockets and chain as the condenser units shown in Figure 4.

80 The grounds G¹, G², G³, G⁴ and Gⁿ, are made in the customary manner and should, as far as possible, be placed, as the antennæ beyond the sphere of influence of each other.

85 It will be readily seen that almost any amount of power can be thus received, controlled and adapted for use not only for modulated power but unmodulated as well. Where it is inconvenient to spread the antennæ circuits to avoid radiation and mutual induction, and it is necessary to lay the antennæ circuits side by side with a consequential loss, nevertheless, there is an operative percentage 90 of gain and amplification. This percentage, of course, can be raised by screening the circuits from each other and yet leaving them open to the incoming electro-magnetic waves. In the drawing the circuits are shown separated by space alone and the radiation from 95 one circuit to another is inversely dependent 100 on the distances between them.

105 The amount of capacity employed in the condensers C¹, C², etc., also has a bearing on the efficiency of each circuit, since for a given wave length the greater the capacity, the stronger the signal becomes. A convenient maximum value for these condensers is .001.

110 While the greater value of the present invention with regard to radio-receiving sets 110 is the amplification which permits the use of a crystal detector with its accompanying freedom of artificially produced noises and the so-called phenomena of static, it, of 115 course, will impart to a tube detector or amplifier the same benefits particularly in regard to distant stations and weak signals.

What we claim is:

1. A receiving and amplifying system for 120 electromagnetic waves comprising a plurality of separate circuits responsive to the same frequency, an auxiliary circuit inductively coupled to said first named circuits and including a plurality of inductances connected in parallel and each coupled to one of said first named circuits, and a condenser shunting said inductances and having a capacity of such value that the received energy is accumulative in said auxiliary 125 circuit.

2. A receiving and amplifying system for electromagnetic waves comprising a plurality of separate antenna to ground circuits responsive to the same frequency, an auxiliary circuit inductively coupled to said first named circuit and including a plurality of inductances connected in parallel and each coupled to one of said first named circuits, and a single condenser shunting said inductances and having a capacity of such value that the received energy is accumulative in said auxiliary circuits. 70
- 5 8. A receiving and amplifying system comprising a plurality of separate antenna to ground circuits responsive to the same frequency each including capacity and inductance, an auxiliary circuit inductively coupled to said first named circuit and including a plurality of inductances connected in parallel and each coupled to one of said first named circuits, and a single condenser shunting said inductances and having a capacity of such value that the received energy is accumulative in said auxiliary circuit. 75
- 10 15 10. A receiving and amplifying system for electromagnetic waves comprising a plurality of collector circuits, each containing capacity, inductance and means for controlling the flow of energy therein, severally insulated, and each having secondary circuits inductively coupled therewith electrically joined in parallel with a variable capacity and forming with the means energized a closed circuit. 80
- 20 3. A receiving and amplifying system for electromagnetic waves comprising a plurality of collector circuits, each containing capacity, inductance and means for controlling the flow of energy therein, severally insulated, and each having secondary circuits inductively coupled therewith electrically joined in parallel with a variable capacity and forming with the means energized a closed circuit. 85
- 25 4. A receiving and amplifying system for electromagnetic waves comprising a plurality of collector circuits, each containing capacity, inductance and means for controlling the flow of energy therein, and severally insulated; means for simultaneously and similarly tuning such circuits; and secondary circuits inductively coupled with each collector circuit and electrically joined in parallel with a variable capacity and forming with a detector and receiver in series a closed circuit. 90
- 30 5. A receiving and amplifying system for electromagnetic waves comprising a plurality of collector circuits, each containing an antenna, variable capacity, inductance, resistance, and ground in series, severally insulated; means for simultaneously and similarly tuning such circuits; and secondary circuits inductively coupled with each collector circuit, and joined in parallel with a variable capacity and forming with the means energized a closed circuit. 95
- 35 6. A receiving and amplifying system comprising a plurality of separate antenna to ground circuits responsive to the same frequency, an auxiliary circuit inductively coupled to said first named circuit and including a plurality of inductances connected in parallel and each coupled to one of said first named circuits, and a variable condenser shunting said inductances and having a capacity of such value that the received energy is accumulative in said auxiliary circuit and forming with a detector and receiver in series a closed circuit. 100
- 40 7. A receiving and amplifying system comprising a plurality of separate antenna to ground circuits responsive to the same frequency and means for controlling the flow of energy therein, an auxiliary circuit inductively coupled to said first named circuit and including a plurality of inductances connected in parallel and each coupled to one of said first named circuits, and a single condenser shunting said inductances and having a capacity of such value that the received energy is accumulative in said auxiliary circuit and forming with the means energized a closed circuit. 105
- 45 8. A receiving and amplifying system comprising a plurality of collector circuits, each containing an antenna, variable capacity, inductance, resistance and ground in series, severally insulated; means for simultaneously and similarly tuning such circuits; and secondary circuits inductively coupled with each collector circuit and electrically joined in parallel with a variable capacity and forming with the means energized a closed circuit. 110
- 50 9. A receiving and amplifying system comprising a plurality of collector circuits, inductively screened from each other but severally open to transmitted waves, each of said circuits containing an antenna, variable capacity, inductance, resistance and ground in series, severally insulated; means for simultaneously and similarly tuning such circuits; and secondary circuits, severally inductively coupled with each collector circuit and electrically joined in parallel with a variable capacity and forming with the means energized a closed circuit. 115
- 55 10. The method of accumulating the energy of electromagnetic waves derived from separate antenna to ground receiving circuits each inductively coupled with secondary circuits joined in parallel with capacity which consists in adjusting the circuits to resonance with one of said waves; inductively transferring the energy in each of said circuits to the secondary circuits in parallel; and accumulating the total transferred energy in said capacity. 120
- 60 11. A receiving and amplifying system comprising a plurality of separate antenna to ground circuits responsive to the same frequency and means for controlling the flow of energy therein, an auxiliary circuit inductively coupled to said first named circuit and including a plurality of inductances connected in parallel and each coupled to one of said first named circuits, and a single condenser shunting said inductances and having a capacity of such value that the received energy is accumulative in said auxiliary circuit and forming with the means energized a closed circuit. 125
- 65 12. The method of accumulating the energy of electromagnetic waves derived from separate antenna to ground receiving circuits each inductively coupled with secondary circuits joined in parallel with capacity which consists in adjusting the circuits to resonance with one of said waves; inductively transferring the energy in each of said circuits to the secondary circuits in parallel; and accumulating the total transferred energy in said capacity. 130

13. In a receiving and amplifying system for electromagnetic waves, having a plurality of separate antenna to ground circuits responsive to the same frequency and an auxiliary circuit inductively coupled to said first named circuits including a plurality of inductances connected in parallel and severally coupled to one of said first named circuits and a condenser shunting said inductances, the method of accumulating the energy from all of said separate circuits which consists in adjusting the capacity of the secondary circuit to such value that the received energy is accumulated in said circuit.
14. In a receiving and amplifying system for electromagnetic waves, having a plurality of separate antenna to ground circuits and an auxiliary circuit inductively coupled to said first named circuits including a plurality of inductances connected in parallel and severally coupled to one of said first named circuits and a condenser shunting said inductances, the method of accumulating the energy from all of said separate circuits which consists in adjusting each of said antenna to ground circuits to resonance with one of said waves; inductively transferring the energy to said secondary circuits; accumulating the aggregate energy in said condenser and discharging the energy through the means energized.
15. In a receiving and amplifying system for electromagnetic waves, having a plurality of separate antenna to ground circuits and an auxiliary circuit inductively coupled to said first named circuits including a plurality of inductances connected in parallel and severally coupled to one of said first named circuits and a condenser shunting said inductances, the method of accumulating the energy from all of said separate circuits which consists in adjusting each of said antenna to ground circuits to resonance with one of said waves; inductively transferring the energy to said secondary circuits, accumulating the aggregate energy in said condenser and translating the accumulated energy.

Signed by us this 11th day of July, 1928.
